(57) **CLAIM**

The ornamental design for a marine port light/port hole cover, as shown and described.

DESCRIPTION

FIG. 1 is a perspective view of a marine port light/port hole cover, showing my new design.

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof; and,

FIG. 7 is a left elevation view thereof.

The use of stippling indicates a contrasting appearance with the adjacent line-shaded portion of the marine port light/port hole cover.
